GUIDE FOR FLEXIBLE SHEET MATERIAL FOR
A FACSIMILE TRANSCEIVER OR SIMILAR
ARTICLE

Robert E. Kalvitis, Fairport, N.Y., assignor to Xerox
Corporation, Rochester, N.Y., a corporation of New
York

Filed May 9, 1968, Ser. No. 11,861

Term of patent 14 years

Int. Cl. D18—03

U.S. Cl. D61—1

FIG. 2

FIG. 3

FIG. 1

FIG. 5

FIG. 4

FIGURE 1 is a left-hand front perspective view of a guide for flexible sheet material for a facsimile transceiver or similar article, showing my new design.

FIGURE 2 is a left side elevational view thereof.

FIGURE 3 is a front elevational view thereof.

FIGURE 4 is a right side elevational view thereof.

FIGURE 5 is a rear elevational view thereof.

I claim:

The ornamental design for a guide for flexible sheet material for a facsimile transceiver or similar article, as shown.
